METAL SHEET DRYING OVEN

August Hormel, Hoboken, N. J., assignor to National-Standard Company, a corporation of Michigan

Application February 4, 1939, Serial No. 254,591

1 Claim. (Cl. 34—12)

This invention relates to an apparatus for drying freshly coated, lacquered or varnished sheet metal plates or the like, and the object of the invention is to provide means for efficiently drying 5 the plates while the same are being moved on a conveyor through a drying chamber or oven.

A further object of the invention is the provision of novel means for either uniformly or selectively controlling the temperature of the heated air within certain areas through the oven.

Another object of the invention is the provision of means for cooling the plates at the exit end of the oven and for exhausting the heated air thereat.

More particularly, the invention contemplates the provision of a lengthy chamber or oven through which the plates to be dried are carried on a conveyor; the provision of heating and air-circulating means arranged in group formation throughout the length of the oven, and the provision of means by which control of the heat in any of said groups may be had. The invention also contemplates the provision of means at the exit end of the drying chamber by which air may be exhausted and the plates cooled immediately prior to their emergence from the drying chamber, so that the dried and cooled plates may be lifted from the conveyor.

In the accompanying drawing, wherein an embodiment of the invention is shown, Fig. 1 is a side elevation of the improved structure; Fig. 2 is a sectional view on the line 2—2 of Fig. 1, looking in the direction of the arrows; Fig. 3 is a transverse sectional view on the line 3—3 of Fig. 1, looking in the direction of the arrows; Fig. 4 is a sectional view at the exit end of the drying chamber, showing the position of the cooling fans; and Fig. 5 is a sectional view on the line 5—5 of Fig. 1, looking in the direction of the arrows.

The drying chamber or oven is in the form of a lengthy structure generally composed of sheet metal and provided with a top or roof 1, side walls 2, and a bottom or floor 3, the structure being supported in a suitably elevated position, upon supporting legs 4, or in any other frame. The walls, top and bottom of the chamber are lined with an insulation or otherwise suitably insulated. At one end, the chamber is open as indicated at 5, this end of the chamber comprising the entrance end, where the conveyor is loaded with the freshly coated plates, the entrance opening being provided with a suitable hood or other protective device 6. Mounted to move through 55 the chamber is an endless chain conveyor, which

has its lower stretch 7 movable below the bottom or floor 3 of the chamber, and its upper stretch 8 movable through the chamber in the direction of the arrows in Fig. 1.

The conveyor is provided with a plurality of spaced racks 9 between which plates 10 to be dried are stacked so that the plates are carried through the chamber by the conveyor in the manner well understood in this art, the dried plates finally emerging out of the open exit end 11 of the drying chamber and being sufficiently cool to permit their being lifted off the conveyor. The structure thus far described is well known in the art.

At the entrance end 5 of the chamber, a double walled enclosure 12 is provided, the spaces 13 between the walls thereof forming passages through which vapors or fumes emanating from the varnished or coated plates just entering the chamber, may be drawn upward into the pipe 14 by means of the suction pump 15 and exhausted therefrom through the pipe 16, to atmosphere. The inner wall 17 of the chamber 12 is formed with a plurality of apertures 18 through which the vapors pass to enter the passages 13 as indicated by the arrows in Fig. 3.

As the plates are carried through the chamber on the upper stretch 8 of the conveyor they are carried past groups of air-circulating units 19, 20, 21 and 22, which circulate heated air through the chamber and around the plates, the air thus circulated being heated by suitable heating means. In the form shown each of the air-circulating groups comprises four ducts 23 joined by a manifold pipe 24, which is connected to a blower 25. The ducts 23 are widened or flared at their lower open ends and extend downward from the blower 25 along one of the side walls 2. The blowers are mounted on the top or roof 1 of the chamber, and the lower open end of each of the ducts is located near the floor 3 and is curved forwardly as indicated at 26 in Fig. 2. Air emanating out of the open end 27 of each of the ducts is blown in a direction toward the opposite side wall 2 of the chamber and against a heated, upwardly curved, deflector plate 28, located in front of a plurality of gas burners 29 located adjacent the wall of the chamber, opposite to that at which the ducts 23 are located. The air blown out of the ducts and circulating in the direction 50 of the arrows as shown in Fig. 2, passes around the plates 10 carried by the conveyor and acts to dry the plates, the air so circulated being drawn upwardly by the suction pipe 30 of the blower and into the blower. The burners are so dis- 55

posed that each burner is located substantially opposite to one of the air ducts 23, and the disposition of the plate 28 is such as to protect the flames of the burners from the air blasts from 5 the ducts.

The arrangement for the thermostatic control for the burners in each group is shown in Fig. 5. It will be there seen that a gas supply pipe 31 projecting on the outside of the chamber or oven 10 from each burner is provided with a control valve 32, the several valves being linked together by rod 33, movement of which is controlled by an arm 34 extending from a thermostatic control 35 positioned within the chamber. Through the arrangement shown, the temperature in the several sections of the chamber can be selectively controlled.

By means of a properly positioned, independently adjusted, thermostatic control 35 for each 20 of the heater groups and accompanying air-circulating groups 19, 20, 21 and 22, it will be apparent that the air temperature prevailing adjacent each group may be readily automatically controlled. The air circulated through the chamber 25 will, of course, be heated by the burners 28 and by contact with the burner plates or deflectors 28.

At the exit end of the chamber a hood 37 is provided and several motor driven fans 38, directed upwardly toward the hood, deliver air blasts past the plates 10 on the conveyor, tending to cool the same so that they may be conveniently handled to enable them to be lifted from the conveyer when they emerge from the 35 exit end of the same. The air blast so directed passes out through exhaust passage 39, leading from the hood 37.

Adjacent the hood 37 is provided a trap-door or valve 40 normally closing an opening in the 40 top or roof 1 of the drying chamber, said door being capable of being held in any desired open or completely closed position to either permit the exit of an air blast from a fan 41 or else confine the blast within the chamber. When the blast is 45 confined, by maintaining the door or valve 40 in closed position, the blast from fan 41 acts as a wall of air under pressure to prevent longitudinal movement out of the chamber of the heated air generated in the chamber by the other burners 50 and blowers. When the door 40 is open, fan 41

used in co-operation with fans 38, will aid in clearing the chamber of vapors and fumes by blowing the same out through the opening.

Briefly, the operation of the structure is as follows:

The coated plates are placed on the conveyor either manually or by mechanical means, at the entrance end 5 of the drying chamber. As the plates are carried by the conveyor through the enclosure 12, the fumes and vapors arising from 1 the plates will be drawn through the apertures 18 in the inner wall 17 and pass out through the exhaust pipe 14. The conveyor thereafter successively carries the plates past the blower groups 19, 20, 21 and 22 which, with their associated 1 burners, direct a continuous flow of heated air around the plates to dry the coating thereon. Each of the burner groups may be controlled thermostatically, as described. When the plates approach the exit end of the drying chamber, 2 cooling blasts of air are directed upwardly past them, so that when they emerge from the egress end 11 of the drying chamber, they are sufficiently cooled to permit of their being manually lifted from the conveyor. 21

What I claim is:

An apparatus of the character described comprising, an elongated heating chamber having an entrance at one end and an exit opening at its other end, a conveyor movable through the chamber for carrying plates therethrough, heating means comprising a plurality of burners arranged along one side wall only of the chamber near the bottom of the chamber, a blower mounted on top of the chamber on the outside of the same, a plurality of air ducts connected to said blower and entrant into the chamber and disposed along the side wall only of the chamber opposite to that where the burners are located, deflector plates arranged in front of the burners and in position 40 to directly deflect air forced across the chamber and impinged against them by the ducts located at the opposite wall of the chamber, the ducts being provided with flared open ends directed toward and facing the deflector plates to thereby 45 direct the air across the chamber against said plates, the chamber having an exhaust outlet connected to the blower. 36 37 38 39 40 41 42 43 44 45
